UNITED STATES PATENT OFFICE.

JOHN R. MITCHELL, OF CHICAGO, ILLINOIS, ASSIGNOR TO W. H. MINER COMPANY, OF CHICAGO, ILLINOIS, A CORPORATION OF ILLINOIS.

DRAFT-RIGGING FOR RAILWAY-TENDERS OR OTHER CARS.

No. 832,870.

Specification of Letters Patent.

Patented Oct. 9, 1906.

Application filed May 22, 1905. Serial No. 261,511.

To all whom it may concern:

Be it known that I, JOHN R. MITCHELL, a citizen of the United States, residing in Chicago, in the county of Cook and State of Illinois, have invented a new and useful Improvement in Draft-Rigging for Railway-Tenders or other Cars, of which the following is a specification.

My invention relates to improvements in railway draft-rigging.

The object of my invention is to provide a convertible draft-rigging, one in which the side castings may be used with cushioning or resisting devices of different kinds or types, as occasion may require—such, for example, as tandem springs, on the one hand, or single springs and friction devices, on the other hand.

My invention consists in the means I employ to practically accomplish this object or result as herein shown or described.

In the accompanying drawings, forming a part of this specification, Figure 1 is a plan view, partly in horizontal section, of a draft-rigging embodying my invention. Fig. 2 is a vertical section on line 2 2 of Fig. 1. Fig. 3 is a vertical cross-section on line 3 3 of Fig. 1. Fig. 4 is a perspective view of the insert or conversion piece of one of the side castings, and Fig. 5 is a section on line 5 5 of Fig. 4.

In the drawings, A A represent the center sills of a tender or other railway-car; A', the front or end sill; A², the buffer-plate, and A³ the carry-iron.

B is the coupler; B', the draw-bar; B², the draw-bar strap or yoke.

C C' C² C³ are the followers, and D D' and E E' tandem-arranged twin springs. Each of the springs preferably has a smaller spring nesting within it.

F F are the side castings or stop-plates, secured to the draft timbers or sills A A by horizontal and upright bolts f f'. Each of the side castings F has a front shoulder or stop f² and a rear shoulder or stop f³ for the front and rear followers to abut against, and forming a chamber or recess between them to receive a removable insert or conversion piece G, having a stop g for the two intermediate followers C' and C² to abut against. Each of the insert or conversion pieces G has

a horizontally-projecting lower flange g', adapted to fit under the horizontally-projecting lower flange f⁴ of the side casting F, which itself fits under the center sill or draft-rigging A, to which the draft-rigging is applied. The followers C C' C² C³ fit and reciprocate between the upper guides f⁵, which are preferably integral flanges on the plates F, and the lower removable guides f⁶, which are secured to the side plates or stop-castings F by bolts f⁷. Each of the insert or conversion pieces G abuts at its front end against the front stop f² and at its rear end against the rear stop f³ of the side plate or stop-casting F and is also additionally secured in place by bolts g², which extend through the sill A and side casting F. The recess, space, or chamber between the front and rear stops f² and f³ of the side casting F is adapted to receive any other suitable type of cushioning or resisting device than the twin tandem springs illustrated in the drawings when the removable insert or conversion pieces G are removed.

As illustrated in the drawings, the side castings F F are of a type adapted to receive, when the insert or conversion pieces G G are removed, one well-known form of draft appliances or cushioning devices and may be readily and quickly converted into form for use with the particular type of draft appliance or cushioning devices illustrated in the drawings by simply putting in place the insert or conversion pieces G G, as shown in the drawings.

As illustrated in the drawings, the side castings F F are shown as cast integrally with each other or in one piece, this integral construction being sometimes used in some kinds of draft-rigging.

I claim—

1. In a draft-rigging, the combination with side castings having each front and rear stops or shoulders with a recess between them and provided with upper integral guides and lower removable guides for the followers, of removable insert or conversion pieces each fitting in the recess of its side casting and abutting at its ends against the stops or shoulders thereof, and provided with a stop or shoulder to serve as an intermediate stop.

for a tandem or converted draft-rigging, substantially as specified.

2. In a draft-rigging, the combination with convertible side castings having integral front and rear stops and integral upper guides for the followers, of removable insert or conversion pieces abutting against said

front and rear stops and provided each with a stop or shoulder, substantially as specified.

JOHN R. MITCHELL.
